CLAIM

The ornamental design for rib pattern for a container, as shown.

DESCRIPTION

FIG. 1 is a top plan view of rib pattern for a container.

FIG. 2 is a side elevational view of the ribs for the container of FIG. 1, the opposite side being identical.

FIG. 3 is an end elevational view of the ribs for the container of FIG. 1, the opposite end being identical.

FIG. 4 is a bottom plan view of the ribs for the container of FIG. 1; and,

FIG. 5 is a perspective view of the ribs for the container of FIG. 1.

The broken lines in the drawings are for illustrative purposes only and form no part of the claimed design.
